UNITED STATES PATENT OFFICE.

HARRY L. KAHN, OF CHICAGO, ILLINOIS.

TROUSERS.

1,185,678.

Specification of Letters Patent. Patented June 6, 1916.

Application filed November 12, 1914. Serial No. 871,674.

To all whom it may concern:

Be it known that I, HARRY L. KAHN, a citizen of the United States, residing at 4710 Grand Boulevard, in Chicago, county 5 of Cook, and State of Illinois, have invented new and useful Improvements in Trousers, of which the following is a specification.

This invention relates to improvements in trousers, and more especially to an improved 10 form of belt loop which is used on the waist band of such garments. Heretofore it has been customary to make the under-garment with a strap or loop attached to the waist band and when suspenders are worn the 15 supporting ends of these are inserted through the straps or loops on the under-garment and then buttoned onto the suspender buttons on the trousers; and when the trousers are supported by a belt instead 20 of suspenders, it is desirable to supply means for supporting the under-garment likewise.

Accordingly the present invention consists in making two or more of the belt loops 25 in such form that a free end is provided on each which extends over the top edge of the waist band of the trousers and down inside, where it may be inserted through a loop on the under-garment and fastened to the in- 30 side of the waist band of the trousers with a snap button.

Such invention is illustrated in the accompanying drawings in which:

Figure 1 is a view in perspective showing 35 a pair of trousers with my improved belt loop used thereon. Fig. 2 is a fragmentary view in perspective showing a portion of the inside of the waist band of the trousers. Fig. 3 is a similar view showing the outside 40 of the waist band. Fig. 4 is a vertical section on the line 4—4 of Fig. 3.

As shown in said drawings, 10 indicates 45 a pair of trousers constructed in the same manner as such garments have heretofore been constructed, with a waist band 11 and several belt loops 12, 12, upon such waist band, through which is inserted a belt 13.

In addition to the belt loops 12 which are 50 of ordinary form, there is provided on each side of the garment a belt loop 15 which is made considerably longer than the loops 12; being secured to the waist band of the

trousers at its lower end and also at a point some distance from its opposite end, leaving a part 16 in the form of a tab or flap 55 to be secured to the inside of the waist band. The construction of these parts is shown in Fig. 4 wherein it is seen that the lower end of the loop 15 is secured between the edges of the pieces of cloth forming the legs and 60 the waist band of the trousers, while it is secured at another point 20 to the top of the waist band; 21 indicating the lining of the trousers with an extra piece of cloth 22 to finish the waist band, and 23 indicating 65 the outer edge of a watch pocket which is provided in the trousers immediately below the waist band. On the free end of the tab 16, and in a corresponding position upon the inside of the waist band, are secured the 70 two parts of a snap button or fastener 25, and in the use of the device the tab 16 may be inserted through the loop 30 on the waist band of the under-garment 31 and then secured by the snap fastener 25. In addition 75 to this use of the device a watch chain or key chain with a ring on the end may be secured in like manner by inserting the tab 16 through the ring and then snapping it in place. 80

I claim as my invention:

1. The combination with a pair of trousers having a waist band, of a belt loop secured at two points to such waist band and having a free end adapted to be folded in- 85 ward over the upper edge of such waist band and secured to the inside thereof.

2. The combination with a pair of trousers comprising a body portion and a waist band secured thereto, of a belt loop having 90 its lower end secured between such body portion and such waist band, such belt loop being secured between its ends to the upper part of the waist band, and having its free end adapted to be folded over the top of the 95 waist band and to be detachably secured to the inside thereof.

In witness whereof, I have hereunto subscribed my name in the presence of two witnesses this 30th day of October, 1914.

HARRY L. KAHN.
